UNITED STATES PATENT OFFICE.

SYDNEY BUCKLEY, OF PHILADELPHIA, PENNSYLVANIA, ASSIGNOR TO NILES-BEMENT-POND COMPANY, OF JERSEY CITY, NEW JERSEY, A CORPORATION OF NEW JERSEY.

CRANE.

1,296,755.

Specification of Letters Patent. Patented Mar. 11, 1919.

Application filed February 17, 1917. Serial No. 149,180.

To all whom it may concern:

Be it known that I, SYDNEY BUCKLEY, a citizen of the United States, and a resident of Philadelphia, in the county of Philadelphia and State of Pennsylvania, have invented certain new and useful Improvements in Cranes, of which the following is a specification, reference being had therein to the accompanying drawings.

- 10 The invention relates more particularly to traveling cranes of the class in which each comprises a movable bridge having two parallel separated elements respectively carrying rails. A hoisting mechanism is provided which consists of a trolley movable along the rails on the bridge and depending load engaging elements which usually extend between the two elements of the bridge.
- 20 In earlier practice it has been customary to provide a single supporting girder for each of the rails upon which the hoisting mechanism traveled, and in order that these girders might be sufficiently stiff and rigid laterally, particularly for cranes with long spans, auxiliary girders have been provided, these being tied to the main girders by suitable transverse and diagonal lattice connections. These auxiliary girders had to be quite heavy in order to carry their own weights, and the metal used in them was entirely inactive for the purpose of carrying the vertical load; and only a part of the metal, that in the upper longitudinal member, was active even for the purpose of providing lateral stiffness. Such compound bridge elements, as heretofore constructed, therefore required a large amount of metal in proportion to the vertical load that they could carry.

One of the objects of the invention is to provide a crane having a bridge structure of novel and improved design whereby the inactive metal is reduced to a minimum. Such a bridge structure is adapted to be built with a long span and to carry heavy loads, at the same time being much lighter and in other ways superior to bridge structures heretofore in use. Other objects of the invention will be apparent from the following specification and from the claims.

In accordance with my invention, the

two girders of each bridge element are made of substantially equal strength and there is provided a supplemental intermediate rail-carrying girder which is supported midway between the two main girders, thus distributing the load between them. In this way I am enabled to make use of the full vertical carrying power of both of the main girders, and all of the metal of each of them is active to carry the load. The required lateral stiffness is secured by suitable cross connections, these including the members which support the intermediate girder. In this way I am enabled to greatly reduce the amount of metal required for carrying a given load; or for the same amount of metal I am enabled to greatly increase the load.

In the accompanying drawings I have illustrated two embodiments of the invention, but it will be understood that the constructions shown are intended to be merely illustrative and are not intended to define or limit the scope of the invention. Particularly, it will be understood that the forms of the girders, the means for connecting them and the various structural details can be varied widely in accordance with the requirements of any particular case or in accordance with the preferences of the designer.

Of the drawings:

Figure 1 is a side elevation of a crane embodying the invention, some of the parts to which the invention does not directly relate being omitted.

Fig. 2 is a transverse sectional view.

Fig. 3 is a fragmentary plan view of one element of the bridge.

Fig. 4 is a fragmentary longitudinal vertical sectional view taken along the line 4—4 of Fig. 3.

Fig. 5 is a fragmentary bottom plan view of one element of the bridge.

Fig. 6 is a transverse sectional view of a bridge element constituting another embodiment of the invention.

Fig. 7 is a fragmentary side elevation of the bridge element shown in Fig. 6.

Referring to the drawings, particularly to Figs. 1 and 2, it will be observed that I have shown a crane comprising a traveling bridge

which is carried at its ends on trucks which travel along rails 1, 1, supported on suitable elevated structures 2, 2. The bridge is made up of two longitudinal elements arranged 5 with a space between them. The two elements are connected at the ends by suitable transverse members 3 as shown in Fig. 2. Preferably there is provided a separate two-wheeled truck element 4 for each end of each 10 bridge element.

For the purpose of moving the bridge as a whole along the rails 1, 1, truck wheels at opposite ends of the bridge are connected with gear wheels 5 which mesh with pinions 15 6 on a shaft 7 which extends longitudinally from one end of the bridge to the other. A motor 8 is provided for rotating the shaft 7, thus serving to move the bridge in one direction or the other as required.

20 Supported on each of the said longitudinal bridge elements is a rail 9. A suitable trolley or hoisting mechanism is provided which is supported on the rails 9, 9, and is adapted to travel along them. The hoisting 25 mechanism as a whole is represented in the drawings by 10, but as this hoisting mechanism of itself constitutes no part of the present invention, detailed description thereof can be omitted. It is sufficient to point 30 out that the hoisting mechanism is provided with a suitable load-engaging device such as the hook 11 which is suspended by a cable or cables 12, passing through the space between the two longitudinal elements of the bridge. 35 By means of a motor 13 the rope can be wound upon or unwound from a drum 14, thus causing the hook with its load to be raised or lowered.

There is a suitable cage 15 which is provided 40 with space for an operator and with suitable controlling devices whereby the movements of the bridge and of the hoisting mechanism can be started, stopped and controlled as required.

45 The present invention relates primarily to the construction of the two main side elements of the bridge, and as these elements are similar to each other it will be sufficient to describe but one of them in detail. In the 50 drawings many of the structural details are omitted or are incompletely shown, as these constitute no part of the invention and can be varied as desired.

55 Each of the side elements of the bridge comprises two separated girders 17 and 18, each girder being individually complete structurally and adapted to carry a vertical load independently of the other girder. The rail 9 is not carried directly upon either of 60 the girders 17 or 18, but upon a supplemental intermediate girder 19 which is supported from the girders 17 and 18 by means of suitable transverse connecting members. So far as certain of the more basic features of 65 my invention are concerned the exact form

of the girders 17 and 18 is immaterial, but I prefer under most circumstances to provide a lattice or truss girder having built-up upper and lower longitudinal members and suitable diagonal or upright connecting 70 members.

As illustrated the upper longitudinal member of each girder comprises a horizontal top plate 20, a vertical web plate 21 and connecting angle bars 22, 22. The lower longitudinal member comprises a horizontal bottom plate 23, a vertical web plate 24 and connecting angle bars 25, 25. Truss or bracing members 26 and 27 are provided for connecting the upper and lower longitudinal 80 members, these truss members being arranged diagonally and forming panels as shown in Figs. 1 and 4. I do not limit myself to any particular arrangement of these truss members, but I find the arrangement 85 shown to be advantageous, this arrangement being particularly desirable as it effects a considerable economy of material. When necessary, additional upright members can be provided but for reasons which will be 90 more clearly set forth below, my improved construction does not require the same amount of bracing that is required for prior constructions.

95 The two girders 17 and 18 are connected at the top by suitable diagonal members 28 and 29, as shown in Fig. 3, and at the bottom by suitable diagonal members 30 and 31, as shown in Fig. 5. There are also provided transverse diagonal members 32 and 33, as 100 shown in Fig. 2.

At intervals throughout the length of the bridge there are provided connecting members which extend perpendicularly from one of the longitudinal members of one girder 105 to the corresponding longitudinal member of the other girder. Preferably these connecting members extend between the upper members of the girders and are located at the panel points where each two diagonal members 26 and 27 join the said longitudinal members. As illustrated in Fig. 4, each connecting member comprises two channel bars 34, 34 placed back to back.

110 Supported on the several pairs of channel bars 34, 34, and preferably positioned midway between the two girders 17 and 18 is the aforesaid supplemental longitudinal girder 19, this being shown as consisting of a rolled steel I-beam. As illustrated, a 115 single I-beam may extend from end to end of the bridge, or at least over a plurality of panel points. At each panel point the I-beam is notched at the bottom to receive the transverse channel bars 34, 34, and at the notch the I-beam is reinforced by means of the angle bars 35, 35, and the bottom plate 36. The aforesaid rail 9 is secured directly to the I-beam 19.

120 It will be observed that with my improved 130

- construction practically all of the metal of the main girders of each of the elements of the bridge is active for the purpose of carrying the vertical stresses resulting from the 5 load and from the weight of the bridge itself. There is no auxiliary girder such as has heretofore been necessary for the purpose of stiffening the structure but which was inactive for carrying vertical stresses.
- 10 By providing two main girders in each element and by dividing the vertical load between them I am enabled to secure the required lateral stiffness without the use of extra metal for that purpose.
- 15 Furthermore, by mounting the rails 9 on the supplemental intermediate girders I am enabled to relieve the upper members of the main girders from all bending stresses due to the direct concentrated pressure of the 20 load. Each supplemental girder is designed as a beam to carry the load and transmit it to the transverse connecting members 34, 34. Inasmuch as the load is transmitted by the members 34, 34 to the main girders at the 25 panel points thereof, no bending stresses occur in the upper members of the girders and these members can be designed to carry compression stresses only. For this reason it is possible to make the top members of the 30 girders considerably lighter than was necessary in earlier constructions in which the part of the top member between each two panel points had to be designed as a beam to carry the concentrated pressure of the 35 load and transmit it to the panel points. Not only am I able to make the top members of the girders lighter but I am also able to omit some of the upright bracing members which were heretofore necessary.
- 40 A further advantage incident to my improved construction is that I am enabled easily and simply to evenly distribute the load on the several wheels of the trucks. As clearly shown in Fig. 2 each rail 9 is positioned midway between the wheels of the corresponding trucks, thus evenly distributing the weight. With earlier constructions having the rail carried directly by one of the girders the load on the wheels was 45 unevenly distributed inasmuch as the rail was much nearer to one wheel of each truck than to the other.
- 50 In Figs. 6 and 7 I have shown another embodiment of the invention, this differing 55 principally in the construction of the upper and lower members of the girders and in the diagonal truss members. As shown, the upper member of each girder comprises a top plate 20^a and two channel beams 21^a, 21^a, arranged back to back and separated from each other. Similarly the lower element of each girder comprises a bottom plate 23^a and longitudinal channel beams 24^a, 24^a, arranged back to back and separated from each other.
- 60 65 The diagonal truss members are in the form

of channel beams 26^a and 27^a arranged similarly to the members 26 and 27 shown in Figs. 1 and 4 and extending at their ends between the channel beams 21^a, 21^a, and 24^a, 24^a, to which they are connected.

70 What I claim is:

1. A traveling crane bridge element comprising a main girder, a rail-carrying girder supplemental to and separated from the main girder, and load transmitting members connecting the rail-carrying girder and the main girder at intervals.

75 2. A traveling crane bridge element comprising two individually complete main girders, a rail-carrying girder supplemental to and separated from the main girders, and load transmitting members connecting the rail-carrying girder and the main girders at intervals.

80 3. A traveling crane bridge element comprising two individually complete main girders, an individually complete rail-carrying girder between the main girders, and connecting members positioned at intervals between the main girders and serving to support the rail-carrying girder.

85 4. The combination in a traveling crane bridge of four individually complete main girders arranged in pairs, two individually complete rail-carrying girders respectively positioned between the main girders of the said pairs, and connecting members positioned at intervals between the main girders of each pair and serving to support the corresponding rail-carrying girder.

90 95 5. The combination in a traveling crane of four individually complete main girders arranged in pairs, two individually complete rail-carrying girders respectively positioned between the main girders of the said pairs, connecting members positioned at intervals between the main girders of each pair and serving to support the corresponding rail-carrying girder, and four end trucks each having two wheels, the trucks being positioned respectively at the ends of the pairs of main girders with the two wheels of each located symmetrically with respect to the corresponding pair of girders.

100 105 6. A traveling crane bridge element comprising two individually complete main girders each comprising an upper longitudinal compression member and a lower longitudinal tension member, an individually complete rail-carrying girder between the 120 main girders, and connecting members extending between the rail-carrying girder and one set of longitudinal members of the main girders.

110 115 7. A traveling crane bridge element comprising two individually complete main girders each comprising an upper longitudinal compression member, a lower longitudinal tension member and diagonal truss members, an individually complete rail-car-

rying girder between the main girders, and connecting members extending between the rail-carrying girder and one set of longitudinal members of the main girders, the said 5 connecting members engaging the longitudinal members at the points where they are engaged by the diagonal members.

8. A traveling crane bridge element comprising two individually complete main 10 girders each comprising an upper longitudinal compression member, a lower longitudinal tension member and diagonal truss members, an individually complete rail-carrying girder between the main girders, and connecting members extending horizontally between the longitudinal members of one set 15 and serving to support the rail-carrying girder.

9. A traveling crane bridge element comprising two individually complete main girders each comprising an upper longitudinal compression member, a lower longitudinal tension member and diagonal truss members, an individually complete rail-carrying 20 girder between the main girders, and connecting members extending horizontally between the longitudinal members of one set 25 and serving to support the rail-carrying girder.

tween the upper longitudinal members and serving to support the rail-carrying girder.

10. A traveling crane bridge element comprising two individually complete main 30 girders each comprising an upper longitudinal compression member, a lower longitudinal tension member and diagonal truss members forming panels, an individually complete rail-carrying girder between the main 35 girders, and connecting members extending horizontally between the longitudinal members of one set at the panel joints and serving to support the rail-carrying girder.

11. A traveling crane bridge element comprising two individually complete main girders, connecting members positioned at intervals between the main girders, and a rolled steel beam constituting an individually 40 complete rail-carrying girder positioned 45 between the main girders, the said beam being notched to receive the connecting members upon which it is supported.

In testimony whereof I hereto affix my signature.

SYDNEY BUCKLEY.
